(57) **CLAIM**

The ornamental design for a tattoo needle assembly, as shown and described.

DESCRIPTION

FIG. 1 is a front perspective view of a tattoo needle assembly of the instant invention.

FIG. 2 is a front view of a tattoo needle assembly of the instant invention.

FIG. 3 is a rear view of the tattoo needle assembly of FIGS. 1 and 2.

FIG. 4 is a side view of the tattoo needle assembly of FIGS. 1 and 2.

FIG. 5 is the opposite side view of the tattoo needle assembly of FIG. 4.

FIG. 6 is a top plan view of the tattoo needle assembly of FIGS. 1 and 2.

FIG. 7 is a bottom plan view of the tattoo needle assembly of FIGS. 1 and 2.

FIG. 8 is a front perspective view of a tattoo needle assembly of the instant invention.

FIG. 9 is a front view of a tattoo needle assembly of the tattoo needle assembly of FIG. 8.

FIG. 10 is a rear view of the tattoo needle assembly of FIG. 8.

FIG. 11 is a side view of the tattoo needle assembly of FIG. 8.

FIG. 12 is the opposite side view of the tattoo needle assembly of FIG. 11.

FIG. 13 is a top plan view of the tattoo needle assembly of FIG. 8.

FIG. 14 is a bottom plan view of the tattoo needle assembly of FIG. 8.

FIG. 15 is a front perspective view of a tattoo needle assembly of the instant invention.

FIG. 16 is a front view of a tattoo needle assembly of the tattoo needle assembly of FIG. 15.

FIG. 17 is a rear view of the tattoo needle assembly of FIG. 15.

(Continued)

FIG. 18 is a side view of the tattoo needle assembly of FIG. 15.

FIG. 19 is the opposite side view of the tattoo needle assembly of FIG. 18.

FIG. 20 is a top plan view of the tattoo needle assembly of FIG. 15; and,

FIG. 21 is a bottom plan view of the tattoo needle assembly of FIG. 15.
